UNITED STATES PATENT OFFICE.

JOHN F. O'CONNOR, OF CHICAGO, ILLINOIS, ASSIGNOR TO WILLIAM H. MINER, OF CHAZY, NEW YORK.

HAND-BRAKE.

1,273,910.

Specification of Letters Patent. Patented July 30, 1918.

Application filed March 30, 1917. Serial No. 158,488.

To all whom it may concern:

Be it known that I, JOHN F. O'CONNOR, a citizen of the United States, residing at Chicago, in the county of Cook and State of Illinois, have invented a certain new and useful Improvement in Hand-Brakes, of which the following is a full, clear, concise, and exact description, reference being had to the accompanying drawings, forming a part of this specification.

This invention relates to improvements in hand brakes.

In the operation of certain types of railway cars, and more particularly in the operation of cars of French railways, it is the custom to have the brakemen apply different and approximately predetermined braking force to the wheels of the various cars of the train on signal from the locomotive. That is, when the engineer desires the train to be braked by hand certain signals are given indicating the desired amount of braking force to be applied, depending upon the conditions under which the train is running. In connection with this method of operating the brakes, certain requirements are necessary and among them an arrangement of brake mechanism such that the brakeman can actuate the same with one hand.

Heretofore, so far as I am aware, the above described method of braking the cars has depended almost entirely upon its uniformity on the skill of the individual brakeman, that is, each brakeman has been required to estimate as best he can from experience the tension on the brakes which he has applied by hand, and obviously, this has entailed great variation, some brakemen applying the tension much greater than others.

The object of my invention is to provide a hand controlled brake rigging for railroad cars wherein the same may be easily operated with one hand, and wherein the braking effect is variable and applied with predetermined degrees of pressure and which renders unnecessary any particular skill on the part of the brakeman.

Another, and more specific object of the invention, is to provide a brake rigging of the type above indicated wherein the operator may set the brakes to any one of several predetermined degrees by merely shifting

the brake wheel or lever to certain predetermined positions.

The invention furthermore consists in the improvements in the parts and devices and in the novel combination of the parts and devices herein shown, described and made the subject matter of the claims.

In the drawing forming a part of this application, Figure 1 is a plan view illustrating the various parts of the hand brake mechanism and showing certain portions of the car framework to which it is attached. Fig. 2 is a longitudinal sectional view of the end portion of a car and taken substantially on the line 2—2 of Fig. 1. And Fig. 3 is a part end elevation, part transverse section taken on the line 3—3 of Fig. 1.

In said drawing 10 denotes the end sill 70 of a car, 11 a transverse sill or needle beam, 12 a channel iron extending between and secured to the sills 10 and 11, and 13 a channel also secured to the sills 10 and 11, the various parts of the end brake mechanism being supported from said sills and beams 12 and 13. The hand wheel 14 is secured at the top end of the brake staff 15, which may be of any desired height corresponding to the type of car to which it is attached. Said 80 brake staff is mounted in an upper bearing 16 and a lower bearing 17 and on the upper bearing bracket 16 is provided a notched indicating plate 18 having a series of notches 19—19 therein, there being four of said 85 notches for the purpose hereinafter described. The hand wheel 14 is provided with a pivoted latch 20 which engages with the notches 19 and by which the hand wheel 14 is locked at any one of the four positions 90 indicated, it being understood that the latch 20 is operated in the usual manner by depressing a pin 21. In Fig. 1, the full lines indicate the position of the parts when no pressure is applied to the brakes and the 95 dotted lines indicate the position of the parts when the maximum pressure from the hand brake mechanism is being applied. These positions correspond, respectively, to the end notches 19—19 and the two intermediate 100 notches correspond to two intermediate degrees of application of the brakes. Secured to the lower end of the brake staff 15 is a lever arm 22 having pivotally connected

thereto a link 23. The link 23 is in turn pivotally connected to one arm 24 of a bell crank which is pivoted to a bracket 25 secured to the end sill 10. The other arm 26 5 of the bell crank has pivotally connected thereto a link 27, the opposite end of the link 27 being pivotally attached to a swinging fulcrum lever 28. The fulcrum lever 28 has an anti-friction roller 29 secured thereto 10 which forms the true fulcrum for the hand brake lever 30. Said fulcrum member 28 is pivotally connected to a cylinder casting 31, as indicated at 32 and the casting 31 is in turn suitably supported by a bracket 33 15 secured to the channel 13.

As will be apparent, by rotating the hand wheel 14, the fulcrum roller 29 will be shifted back and forth, the limits of the movement being indicated by the full lines 20 and dotted lines in Fig. 1, to thereby shift the fulcrum for the hand brake lever 30, for the purpose hereinafter described.

The hand brake lever has pivotally attached thereto an adjustable connecting link 25 133, the opposite end of said link 133 being pivotally attached to the cylinder lever 34 in a well known manner. The cylinder lever 34 is adjustably pivoted to an arm 35 as customary and its free end is slidably connected 30 with the piston 36 of the air cylinder 37 of the brake rigging. The cylinder lever 34 has connected thereto the usual pull-rod 38 that operates the brake beam and shoes, as will be understood.

35 Mounted within the cylinder 31 is a spring 39 of any predetermined, relatively high capacity. Seated against the outer end of the spring 39 is a piston 40 from which extends a piston rod 41 outside of the casing and 40 which is in turn pivotally connected to the hand brake lever 30, as indicated at 42. In the normal position of the parts, the spring 39 is maintained under its maximum compression so that it is at all times adapted to 45 exert pressure against the hand brake lever when desired.

In the normal position of the parts, the fulcrum proper 29 is alined with the piston rod 41 so that the hand brake lever remains 50 stationary or inactive. When the hand brake wheel 14 is oscillated, say to the second notch, it is apparent that the fulcrum proper 29 will be shifted out of alinement with the piston rod 41 and toward the out- 55 side of the car. This permits the spring 39 to expand and to swing the lever 30 about the fulcrum 29. It is obvious, that the effective force applied to the connecting link 133 from the lever 30 will depend upon the 60 ratio of the lever arms of the lever 30. In other words, when the fulcrum 29 is shifted only a short distance, the ratio of lever arms is high and, due to the fact that the lever is operated as one of the third class, the effective force of the spring on the link 133

will be considerably reduced. If the hand wheel 14 is stopped at the second notch, it is apparent that the force exerted by the spring 39 will always be the same on the link 133 and consequently on the brakes themselves. If now, the wheel 14 is shifted to the third notch, it is apparent that the ratio of the lever arms of the lever 30 is decreased so that the effective force of the spring is correspondingly increased. Similarly, when 70 the wheel 14 is shifted to the fourth notch, that is, to the dotted position, the ratio of the lever arms will be still further decreased and consequently the effective force of the spring 39 similarly augmented. It is evident, that by properly locating the positions of the notches on the indicator plate 18 and determining the different ratios of lever arms of the lever 30, the braking force applied can be adjusted to predetermined 75 amounts. In this manner, the brakemen have only to shift the hand wheels 14 to the proper notch in accordance with the signals given them and all brakes will be applied uniformly throughout a train, thus elimitating 80 the personal equation which has heretofore been necessary to be taken into account.

On the beam 12, a bracket 43 is attached which limits the movements of the lever 30, as will be apparent. At the rear of the 95 cylinder 31, is mounted an adjustable follower 44, the adjustment being effected by an adjusting bolt 45 so that the spring compression can be regulated as desired. The air cylinder piston 36 is slotted, as indicated 100 at 46 in the usual manner so as to permit movement of the cylinder lever 34 independent of the actuation of the air cylinder.

I have herein shown and described what I now consider the preferred embodiment of 105 my invention but the same is merely illustrative and I contemplate all changes and modifications that come within the scope of the claims appended hereto. It is also obvious that the improvements are capable of 110 application to many structures and, except so far as limited by the claims, I do not wish to be restricted to the use of the improvements to a car brake rigging.

I claim:

1. In a brake rigging, the combination with the cylinder lever, of an auxiliary lever, a connection between said levers, and manually controlled means for exerting different and predetermined forces on said auxiliary 120 lever to thereby correspondingly actuate the brakes.

2. In a brake rigging, the combination with the cylinder lever, of an auxiliary lever, a connection between said levers, and manually controlled means for exerting different and predetermined forces on said auxiliary 125 lever to thereby correspondingly actuate the brakes, said means including a source of stored energy and an adjustable element for 130

varying the lever arm ratios of said auxiliary lever.

3. In a brake rigging having power controlled brakes, the combination therewith of 5 auxiliary, manually controlled, adjustable means for applying variable predetermined braking forces.

4. In a brake rigging, the combination with a cylinder lever and hand brake lever, 10 of means for actuating said hand brake lever, and means for varying the lever arm ratios of said hand brake lever.

5. In a brake rigging, the combination with a cylinder lever and a hand brake lever, 15 of an adjustable fulcrum for the hand brake lever whereby the braking forces applied through the hand brake lever can be varied, a connection between the hand brake lever and the cylinder lever, and means permitting 20 the cylinder lever to move independently of the hand brake lever and said connection when the cylinder lever is actuated from the cylinder.

6. In a brake rigging, the combination 25 with the cylinder lever and the hand brake lever, of an adjustable fulcrum for the hand brake lever whereby the braking forces applied through the hand brake lever can be varied, and manually operable means for 30 shifting said fulcrum.

7. In a brake rigging, the combination with the cylinder lever, of a source of stored energy, means interposed between said source and the cylinder lever for thereby actuating the latter, and manually adjustable means for varying the effective force of said energy while actuating said cylinder lever.

8. In mechanism of the character described, the combination with a lever, of 40 means for actuating the lever, and manually adjustable means for varying the lever arm ratios of said lever when actuated by said actuating means.

9. In mechanism of the character described, the combination with a lever, of 45 means for actuating said lever, and a man-

ually adjustable fulcrum for said lever to thereby vary the ratio of the lever arms when the lever is actuated by said means.

10. In mechanism of the character de- 50 scribed, the combination with a lever, of a spring normally under compression and adapted to actuate said lever, of an adjustable fulcrum for said lever to thereby vary the effective force of said spring thereon. 55

11. In a brake rigging, the combination with a cylinder lever, a hand brake lever, and connections between said levers, of a spring adapted to exert pressure on the hand brake lever, and a manually adjustable 60 fulcrum for the hand brake lever.

12. In a brake rigging, the combination with a cylinder lever, a hand brake lever and connections between said levers, of a 65 brake staff having means by which it may be operated, a spring adapted to exert pressure on the hand brake lever, and means connected to said brake staff for shifting the fulcrum of the hand brake lever.

13. In a brake rigging, the combination 70 with a hand brake lever having means extending therefrom for actuating the brakes, of a brake staff, a spring arranged to exert pressure on said lever, a pivotally mounted fulcrum for said lever, and means interposed 75 between said brake staff and fulcrum member for shifting the position of the latter.

14. In a brake rigging, the combination with a hand brake lever, of a spring arranged to exert pressure on said lever, a 80 movably mounted fulcrum for said lever, a brake staff, connections extending between said brake staff and fulcrum member for shifting the position of the latter upon movement of the brake staff, means for turning the brake staff, and means for indicating 85 predetermined positions of said brake staff.

In witness that I claim the foregoing I have hereunto subscribed my name this 27th day of March, 1917.

JOHN F. O'CONNOR.
